A. D. GROVER.
VENDING MACHINE INDICATOR.
APPLICATION FILED FEB. 2, 1918.

1,407,063.

Patented Feb. 21, 1922.

FIG. 2.

FIG. 1.

INVENTOR -

Albert D. Grover.

by A. A. Thomas
Atty.

UNITED STATES PATENT OFFICE.

ALBERT D. GROVER, OF NEW YORK, N. Y., ASSIGNOR TO AUTOSALES CORPORATION, A CORPORATION OF NEW YORK.

VENDING-MACHINE INDICATOR.

1,407,063.

Specification of Letters Patent. Patented Feb. 21, 1922.

Application filed February 2, 1918. Serial No. 215,023.

To all whom it may concern:

Be it known that I, ALBERT D. GROVER, a citizen of the United States, and resident of New York city, in the county of New York and State of New York, have invented certain new and useful Improvements in Vending-Machine Indicators, of which the following is a specification.

My invention relates to vending machines intended to be operated by the insertion of a coin, and its object is to provide means for indicating the condition of the machine as regards the supply of goods in the magazine. The indicator of my invention is such that it may be felt from the outside of the machine, so that the person in charge of the machine can readily determine, by a mere touch, whether it needs replenishing.

My invention is particularly applicable to vending machines of the kind that are operated in theatres or like places. In these so-called theatre machines it is necessary to attend to many machines in a very short time. It is, therefore, essential that the collector should be able to determine very quickly whether a machine needs attention. Obviously, this could not be done if every machine had to be opened. Nor is it practical to have a sight indicator, such as a strip of glass covering the opening through which the goods may be seen. Such an indicator is objectionable and impractical for two reasons: In the first place, theatres are dark when collections are made from the vending machines; secondly, the glass of the sight opening would soon be broken and the goods tampered with.

Therefore, I have provided a device which the attendant or collector in charge of the machines can feel when passing quickly between the rows of chairs where the machines are attached.

The device which constitutes my present invention is a specific improvement upon the vending machine indicator which forms the subject-matter of an application filed jointly by Edwin B. Potts and myself on November 3, 1917, Serial No. 200,177. I do not, therefore, herein claim broadly an indicator which is adapted to be felt from the outside of the machine to determine the condition of the supply of goods in the magazine,

as that is claimed in the aforesaid joint application.

In the accompanying drawings

Fig. 1 is a front view in elevation of a vending machine equipped with my invention; and

Fig. 2 is a side elevation, partly in section, on line 2—2 of Fig. 1, the indicator being shown in normal position.

The indicator of my invention is applicable to various kinds of vending machines, and for the sake of illustration I have shown in the drawings a theatre machine somewhat like that shown in the application of Anthony Coslegia, Serial No. 186,843, filed August 18, 1917, or my pending application, Serial Number 187,206, filed August 20, 1917. In the present case I have not considered it necessary to show a complete delivery mechanism, as that does not in and of itself form part of my invention. Any suitable mechanism may be employed for delivering the packages.

In the drawing I have shown a delivery device in the form of a cylinder 1 pivoted at 2 and 3 in the sides of the casing C of the machine. The delivery cylinder 1 is adapted to be operated in any suitable manner, as by means of a hand-knob 4 at the front of the machine, when a proper coin is inserted into the coin-slot 5. The operative connections between the knob 4 and the delivery cylinder 1 are not shown in this case, as they form no part of my present invention, but reference may be had to the applications referred to. If desired, the delivery cylinder 1 may be operated by a knob at the side of the casing and attached directly to the cylinder. For the sake of brevity and convenience, the cylinder 1 will hereinafter be referred to as the delivery mechanism, by which I mean any suitable form of mechanism for that purpose.

The goods or packages to be sold are contained in a magazine M of suitable construction. This magazine is secured within the casing by any suitable means. In the present instance, the front wall of the magazine 100 is spaced slightly from the front wall of the casing, thus providing a narrow space or chamber S. The packages in the magazine M are indicated at P. The lowermost

package rests on top of the delivery cylinder. When this cylinder is operated, the bottom package is discharged into the chamber 6 at the bottom of the casing, whence 5 it may be removed through side openings 7.

The indicator of my present invention is preferably mounted in the chamber S and comprises a pawl 8 pivoted at 9 between a pair of spaced lugs 10 secured to the front 10 wall of the magazine. At its lower end the pawl 8 is provided with an inner extension 13 and an outer extension 12. The inner extension projects through a slot 11 into the magazine M into engagement with the goods 15 or packages P. The outer extension 12 projects outside of the casing through a slot or opening 14 formed in the front plate of the casing. Suitable spring means such as leaf spring 15 may be employed to urge the 20 pawl inwardly when free to be moved. The spring 15 is secured at 16 to the front wall of the magazine, while the other end 17 engages the pawl 8. Any other suitable spring means may be associated with the pawl 8, 25 or the spring means may be altogether omitted if desired.

As long as there is a predetermined number of packages in the machine (say, three for example, as shown in Fig. 2), the outer 30 extension 12 of the pawl 8 projects out of the casing and is firmly held in that position by the package or goods which the inner extension 11 engages. When, therefore, the collector passes his finger along the machine 35 and encounters the projection 12, he is at once informed that the machine does not need replenishing.

However, should the supply of goods be exhausted to a predetermined point (as for 40 instance, when there are two or less packages in the machine) the spring 15 will force the pawl 8 inwardly and the outer head 12 will not project out of the casing. When, therefore, the collector does not feel 45 the projection 12, as he passes his hand over the front of the machine, he is at once informed that the machine needs attention.

The spring 15 may be entirely omitted, in which event the head 12 would still project 50 out of the casing when the supply of goods is exhausted below the predetermined limit, but the head 12 would then be free to be pushed inwardly under the pressure of the collector's fingers. This yielding of the head 55 12 would inform the collector that the machine requires attention.

It will be observed that the inner extension 11 of the pawl 8 is so shaped as to set the head 12 automatically into normal or 60 indicating position when the goods are dropped into the magazine. When the collector, therefore, fills the machine, he need pay no attention to the indicator, as that will set itself into the right position by the 65 mere insertion of the goods.

Having thus described my invention, what I claim as new, and desire to secure by Letters Patent of the United States, is:

1. In a vending machine, an outer casing 70 provided with a magazine for containing the vendable goods, mechanism for delivering the goods from said magazine, and a pawl pivoted at one end within said casing, the other end of said pawl being provided with an inner head or extension and 75 an outer head or extension, said inner extension projecting into engagement with the goods in the magazine as long as there is a predetermined supply thereof in the magazine, said outer extension projecting out of 80 the casing when said inner extension is in engagement with the goods in the magazine, but adapted to be moved into the casing when the supply of goods has fallen below said inner extension, whereby said outer extension acts as an indicator that may be felt from the outside of the machine to ascertain the condition of the supply of goods 85 in the magazine.

2. In a vending machine, an outer casing 90 provided with a magazine for containing the vendable goods, mechanism for delivering the goods from said magazine, a pawl pivoted at one end within said casing, the other end of said pawl being provided with 95 an inner head or extension and an outer head or extension, said inner extension projecting into engagement with the goods in the magazine as long as there is a predetermined supply thereof in the magazine, said outer extension projecting out of the magazine when 100 said inner extension is in engagement with the goods in the magazine, and a spring for actuating said pawl to move said outer extension into the casing when said inner extension is out of engagement with the goods in the magazine, whereby said outer extension acts as an indicator that may be felt 105 from the outside of the machine to ascertain the condition of the supply of goods in the 110 magazine.

3. In a vending machine, an outer casing provided with a magazine for containing the vendable goods, the front wall of said casing and the front wall of said magazine 115 being each provided with an opening, mechanism for delivering the goods from said magazine, there being a narrow space or chamber between the front wall of said casing and the front wall of said magazine, 120 and a pawl pivoted at one end in said space or chamber, the other end of said pawl being provided with an inner head or extension and an outer head or extension, said inner extension projecting through the opening 125 in said magazine into engagement with the goods as long as there is a predetermined supply thereof in the magazine, said outer extension projecting out of the casing through the opening in the front wall there- 130

of when said inner extension is in engagement with the goods in the magazine, but adapted to be moved into the casing when the supply of goods has fallen below said 5 inner extension, whereby said outer extension acts as an indicator that may be felt from the outside of the machine to ascertain the condition of the supply of goods in the magazine.

- 10 4. In a vending machine, an outer casing provided with a magazine for containing the vendable goods, the front wall of said casing and the front wall of said magazine being each provided with an opening, mechanism 15 for delivering the goods from said magazine, there being a narrow space or chamber between the front wall of said casing and the front wall of said magazine, a pawl pivoted at one end in said space or chamber, the other 20 end of said pawl being provided with an inner head or extension and an outer head or extension, said inner extension projecting through the opening in said magazine into engagement with the goods as long as there 25 is a predetermined supply thereof in the magazine, said outer extension projecting out of the casing through the opening in the front wall thereof when said inner exten-

sion is in engagement with the goods in the magazine, and a spring for actuating 30 said pawl to move said outer extension into the casing when said inner extension is out of engagement with the goods in the magazine, whereby said outer extension acts as an indicator that may be felt from the outside 35 of the machine to ascertain the condition of the supply of goods in the magazine.

5. In a vending machine, an outer casing provided with a magazine for containing the vendable goods, mechanism for delivering the goods from said magazine, and a member pivoted at one end within said casing, the other end of said member being provided with indicating means comprising a part adapted to project out of the casing 40 and a part adapted to engage the goods in the magazine, so that said first-named part is held firmly out of the casing as long as the supply of goods is in a predetermined condition, said indicating means being automatically set into normal position by the goods in the magazine.

In witness whereof, I hereunto subscribe my name this 24th day of January, 1918.

ALBERT D. GROVER.
